UNITED STATES PATENT OFFICE.

PHILLIPS P. BOURNE, OF WINCHESTER, AND OTTO NONNENBRUCH, OF BOSTON, MASSACHUSETTS, ASSIGNORS TO WORTHINGTON PUMP AND MACHINERY CORPORATION, OF NEW YORK, N. Y., A CORPORATION OF VIRGINIA.

REVERSING AND CONTROL MECHANISM FOR INTERNAL-COMBUSTION ENGINES.

Application filed October 1, 1923. Serial No. 665,766.

This invention relates to a reversing and speed control mechanism for internal combustion engines, and is more especially adaptable to the type of liquid fuel injected engine operating on the Diesel principle, though it is equally applicable to other types of internal combustion engines.

One of the primary objects of the invention is to provide a simple and satisfactory construction by which the fuel injection mechanism will automatically function on engine reversal in such a way that the engine continues to operate under the same conditions of fuel injection and combustion after reversal in either direction has been effected.

A further feature resides in automatically adjusting the timing of the fuel injection to correspond to the predetermined direction of rotation by providing a series of fuel eccentrics mounted on a single integral sleeve having a limited rotary movement on the crank shaft of the engine and operated by a device providing lost motion on reversal.

With the above features in mind a preferred form of the invention has been illustrated in the accompanying drawings, in which—

30 Figure 1 is a side elevation, partly in section, of an engine embodying the present invention;

35 Figure 2 is a top plan view of the control mechanism portion of the engine;

Figure 3 is an end elevation, partly in section, and showing the control gear;

Figure 4 is a sectional view on the lines 4—4 of Figs. 3 and 6.

Figure 5 is a sectional view on the line 40 5—5 of Fig. 4;

Figure 6 is a sectional view on the line 6—6 of Fig. 1; and

Figure 7 is a sectional view showing the starting air valve actuating mechanism.

45 Referring to the drawings, the engine is of the usual type comprising the four cylinders 10, 11, 12 and 13, connected in the customary manner with the crank shaft 14, the end of which is extended as at 15 and has secured thereto, by a key 16, the gear 17 the hub of which has a cut-away sector indicated at 18 and best shown in Fig. 5.

Sliding onto the end 15 of the crank shaft 14 is a sleeve 19 having the eccentrics 20, 21, 22 and 23. This sleeve carries, on the end 55 adjacent the hub of the gear 17, a lug 24 which engages with either face of the sector 18 formed by cutting away a portion of the hub of the gear 17 so that as the crank shaft 14 changes direction of rotation 60 the sleeve 19 automatically moves to one or the other of its extreme positions. The eccentric straps 25 carrying rollers 26 and controlled links 27 connecting them with the shaft or stud 28 work on the said eccentrics 65 20 to 23 inclusive, and thus the plunger stems 29 of the fuel injectors are actuated on movement of the crank shaft 14 and, as soon as the engine is reversed, automatic timing is accomplished by reason of the 70 lost motion connection formed by the sector 18 and the lug 24.

The air starting mechanism includes the air manifold 30, from which the supply of air to the respective cylinders through pipes 75 71 is controlled by the air valves 31, one for each cylinder, actuated through the medium of the rocker arms 32 oscillating on the shaft 33 and maintained under tension by springs 34, each arm 32 having a 80 roller 35 for engagement with the cam sleeve 36 which has integral therewith series of ahead and astern cams; and said cam sleeve 36 is mounted with a sliding fit on the lay shaft 37 and is keyed for rotation therewith by the key 38. The lay shaft 37 is supported in bushings 39 and, at one side, has a shroud 40 to prevent endwise movement; a gear 41 keyed to the lay shaft as at 42 meshes with the gear 17 on 90 the crank shaft and is driven thereby.

For controlling and reversing the engine, the cam sleeve 36 is engaged by the forked shifting member 43 which is pinned at 44 to the shaft 45 supported in bosses 46. One 95 end of the shaft 45 carries a bell crank lever 47, one arm 48 of which is connected with the master air valve, not shown, which controls the supply of air from pipe 72 to the manifold 30, while the other arm 49 is connected by a link 50 with the lower end 51 of the air reverse lever 52 pivoted at 53 to move on a quadrant 54; thus, by moving the air reverse lever 52 the master

air valve is actuated and, also, the cam sleeve 36 is moved to position the cams for actuation of the air starting valves for "ahead" or "astern" running direction of the engine.

The engine shown is a solid injection engine, and it will be understood that the air supplied to manifold 30 through pipe 72, and from manifold 30 to the engine cylinders through pipes 71, is only for starting the engine in either direction, this starting air being admitted to and cut off from manifold 30 by a hand valve (not shown), and its admission controlled by the master air valve (not shown) operated by lever 52, as above described, this starting air thus being admitted to the cylinders only until the engine is started and firing on fuel, the admission of which is controlled by lever 55. The reversal operation, therefore, as usual in such engines, is that the fuel is cut off and the engine stopped, the starting air is then admitted to pipe 72 by opening the hand valve, the lever 52 is then operated to open the master air valve for the admission of starting air to manifold 30, and to shift the cam sleeve 36 longitudinally on shaft 37 to shift the cams for the reverse operation of the engine. After thus starting the engine, the lever 55 is operated to admit fuel, and on firing the air is cut off from pipe 72 by hand valve (not shown) and the normal operation of the engine is resumed.

The engine is governed, and the fuel controlled, by a fuel control lever 55 which also is pivoted at 53, the same as the air reversing lever 52, and works on the quadrant 54. The lower end of the fuel control lever 55 is provided with an extension 56 which has pivoted thereto at 57 a floating bell crank lever 58, one side of which is connected by means of the link 59 to the arm 60 for moving the fuel control shaft 61, while the other side of the floating lever 58 is connected to an adjustable link 62 which connects with the crank arm 63 on the end of the shaft 64 which has pinned thereto at 65 the forked member 66 engaging with the annulus 67 in the slidable element 68 controlled by the weights 69 through the medium of the arm 70.

The pump control shown forms no part of the present invention, and any other suitable control may be used. As shown, the fuel control shaft 61 is mounted eccentrically so that its rotation raises or lowers, and thus shifts, the fulcrums of the levers 1, the other ends of which are connected to the pump plunger actuators 29, so that the levers 1 are rocked by the plungers at each movement, and thus through rods 2, engaging the valve stems 3, open the suction valves of the pump, during the discharge stroke, at points determined by the

position of the control shaft 61, and thus by-pass a portion of the oil under governor control.

It will be seen from this construction that the speed control is effected through the medium of the fuel control lever, but that the governor control gear is such that the operation of the fuel control lever changes the location of the fulcrum of the floating bell crank lever 58 which shifts the fuel control shaft 61, the movement of which controls the opening of the suction valve during the discharge stroke of the pump and by-passes more or less of the fuel so as to regulate the amount of fuel injected into the cylinders, reducing the quantity of each fuel injection as the fuel control lever is moved towards its "no fuel" position.

It will be understood that the invention is not limited to the specific construction or arrangement of parts illustrated, but that many modifications may be made while retaining the invention defined by the claims.

We claim:

1. In an internal combustion engine, the combination with a plurality of working cylinders and their pistons and the crank shaft driven thereby, of fuel injectors, a circumferentially movable sleeve mounted on said shaft, eccentrics carried by said sleeve arranged to actuate the fuel injectors, and means arranged to provide a limited lost motion of the sleeve for automatically continuing the operation of the engine after reversal under the same conditions of fuel injection and combustion.

2. In an internal combustion engine, the combination with a plurality of working cylinders and their pistons and the crank shaft driven thereby, of fuel injectors, a circumferentially movable sleeve mounted on said shaft, eccentrics carried by said sleeve arranged to actuate the fuel injectors, and a sector and lug associated with said shaft and sleeve and arranged to co-operate with each other to provide a limited lost motion of the sleeve for automatically continuing the operation of the engine after reversal under the same conditions of fuel injection and combustion.

3. In an internal combustion engine, the combination with a plurality of working cylinders and their pistons and the crank shaft driven thereby, of fuel injectors, a circumferentially movable sleeve mounted on said shaft, eccentrics carried by said sleeve arranged to actuate the fuel injectors, means arranged to provide a limited lost motion of the sleeve for automatically continuing the operation of the engine after reversal under the same conditions of fuel injection and combustion, air starting mechanism including air valves, a lay shaft driven from the aforesaid shaft, and an axially movable

sleeve on said lay shaft and driven thereby, said sleeve carrying air valve actuators and being movable axially to bring different combinations of actuators into co-operation with the air valves for starting and reversing.

4. In an internal combustion engine, the combination with a plurality of working cylinders and their pistons and the crank shaft driven thereby, of fuel injectors, a circumferentially movable sleeve mounted on said shaft, eccentricities carried by said sleeve arranged to actuate the fuel injectors, a sector and lug associated with said sleeve and shaft and arranged to co-operate with each other to provide a limited lost motion of the

sleeve for automatically continuing the operation of the engine after reversal under the same conditions of fuel injection and combustion, air starting mechanism including 20 air valves, a lay shaft driven from the aforesaid shaft, and an axially movable sleeve on said lay shaft and driven thereby, said sleeve carrying air valve actuators and being arranged to be moved axially to bring different combinations of actuators into co-operation with the air valves for starting and reversing. 25

In testimony whereof, we have hereunto set our hands.

PHILLIPS P. BOURNE.
OTTO NONNENBRUCH.
